MAGNETIC INDUCTION ACCELERATOR

Konrad Gund, Erlangen, Germany

Application October 28, 1950, Serial No. 192,733

Claims priority, application Germany
October 31, 1949

6 Claims. (Cl. 313—62)

1

This invention relates to a magnetic induction accelerator for electrically charged elementary particles, e. g., electrons, and is particularly concerned with an accelerator for therapeutic irradiation.

The term "magnetic induction accelerator" refers to a device in which elementary particles, e. g., electrons, are moved along approximately circular paths in a magnetic guiding field and accelerated by means of a magnetic flux of increasing strength passing through said circular paths.

One of the principal objects of the invention is to reduce the weight of the magnetic iron in an accelerator of the above-noted type so as to obtain appreciable reduction of its total weight and bulk for the purpose of adapting it for use as a radiation source in therapeutic irradiation apparatus.

In accordance with the invention, the guiding field poles are so dimensioned that the guiding field strength increases, as usual, in the neighborhood of the equilibrium orbit up to the final acceleration of the electrons in proportion with the accelerating field while magnetic saturation occurs therein at an intensity or strength of the acceleration which is relatively small compared with its final intensity.

The invention is based on recognition of the fact that the electrons fill the evacuated acceleration tube or chamber in the form of a broad band only at the commencement of acceleration, and concentrate quickly toward the equilibrium orbit, oscillating finally about said orbit within a radially narrow zone. The guiding field therefore has to be as wide as the evacuated tube only at the start of acceleration, so as to secure all electrons in their orbital equilibrium paths. The width of the guiding field may diminish with the narrowing of the electron bundle. In other words only in a portion of the guiding field which is present at the start of acceleration need the field strength increase corresponding to the 1 : 2 condition up to the final acceleration along the equilibrium orbit. The magnetic iron of the guiding field poles outside of the region near the equilibrium orbit and also the yoke may therefore be generally of smaller weight and dimensions than heretofore.

In an accelerator having common excitation for the accelerating and the guiding fields, a contraction of the electron bundle to the neighborhood of the equilibrium path takes place, as taught by experience, at a time when the total

2

excitation of the accelerator reaches a low multiple of the value which is present at the injection of the electrons. The magnetic saturation within the border zones of the guiding field poles therefore should begin at least at the tenfold value of the common excitation which is present upon injection of the electrons.

During experimenting it was found suitable to permit saturation of the guiding field poles to about one-half of their width at the oppositely positioned pole surfaces. In this case the saturation of the circular poles only at the outer marginal zone of the pole surfaces is preferable to a saturation including the inner marginal zone, because a greater flux is saved by narrowing the guiding field width outside of the equilibrium orbit, on account of the greater surface permeated by the flux, than by corresponding diminution of the width of the guiding field within the equilibrium circuit.

The arrangement according to the invention made it possible, e. g., in the case of an accelerator for a final energy of 12 m. e. v., in addition to a broadening of the guiding field by 30%, to 15 reduce the magnetic flux by 15% (as compared with an otherwise similar prior structure) and to reduce thereby the cross-sectional area of the yoke of the electromagnet, which is common to the accelerating and to the guiding field, to such an extent as to result in reduction of the weight of the structure by about 10%.

The objects and features noted in the foregoing outline and additional objects and features will appear from the following description of the 30 accompanying drawing which shows in diagrammatic partly sectional front elevational view an example of an accelerator made in accordance with the invention.

On the closed yoke 1 shown in the drawing 40 are secured the oppositely disposed accelerating pole pieces 2, 3 and the guiding field poles 5, 6 which are integral therewith and separated from the accelerating poles by the slots 4. The accelerating pole pieces 2, 3 are thus magnetically 45 coupled to the yoke 1 and form across the air gap therebetween a path for the magnetic flux of the accelerating field which extends centrally of the tube 9. The air gap between the accelerating pole pieces is subdivided by means of magnetic iron plates 7, 8, in order to keep down the straying field near the edge of the air gap. The toroidal accelerating tube or chamber 9 is disposed between the opposite guiding field poles 5, 6 and provides therein a closed orbital path 55 along which the electrons are accelerated. The

guiding field poles 5, 6 form an inner guiding field zone which embraces the equilibrium paths of the electron particles within the tube 9 and are provided with generally ring-shaped magnetic pole shoes 10, 11 which are integral therewith and extend generally radially outwardly therefrom, forming an outer guiding field zone. The pole shoes 10, 11 are about as wide as the guiding field poles 5, 6 and somewhat wider than the tube 9. These shoes are so dimensioned that their saturation begins at the most at such time when the excitation caused by the coils 12, 13 has reached about tenfold value of the excitation at the injection of the electrons. From this moment on, the guiding field flux increases in accordance with the 1:2 condition only in the poles 5, 6 and not any more in the shoes extending therefrom. In other words, the field strength in said inner guiding field zone controlled by the poles 5, 6 increases substantially proportional with the field strength of the acceleration field, while the ring-shaped pole shoes 10, 11 become magnetically saturated at a field strength of the acceleration field which is small as compared with the final field strength thereof to cause further increase of the field strength in said outer guiding field zone which is less than proportional with the further increase of the field strength in said acceleration field. Accordingly, the total flux in the yoke does not increase to an extent as would be the case if the 1:2 condition were maintained for the entire guiding field.

Certain structural and functional features of the accelerator, which are not shown in the drawing or explained in the foregoing specification may be had by consulting copending applications Ser. Nos. 192,731, 192,732 and 226,729, filed October 28, 1950, and features disclosed in these copending applications which are deemed pertinent to the present invention should be treated as if they had been included herein.

The appended claims define what is believed to be new and desired to have protected by Letters Patent of the United States.

I claim:

1. A magnetic induction accelerator for electrically charged particles comprising an annular tube providing therein a closed orbital path along which the particles are accelerated, a magnetic yoke, accelerating pole pieces magnetically coupled to said yoke forming a path for the mag-

netic flux of the acceleration field which extends centrally of said tube, magnetic guiding field poles projecting generally radially outwardly from said acceleration pole pieces forming outside of said tube on opposite sides thereof annular opposing inner surfaces defining an inner guiding field zone which embraces the equilibrium paths of said particles within said tube, and generally annularly extending magnetic pole shoes projecting generally radially outwardly from said guiding field poles forming outside of said tube on opposite sides thereof annular axially opposing inner surfaces defining an outer guiding field zone.

15 2. The structure defined in claim 1, wherein the radial width of said ring-shaped magnetic pole shoes defining said outer guiding field zone corresponds approximately to the radial width of the guiding field poles which define said inner guiding field zone.

20 3. The structure defined in claim 1, wherein said acceleration pole pieces and the guiding field poles and said ring-shaped pole shoes are formed by common integral members.

25 4. The structure defined in claim 1, wherein said acceleration pole pieces and the guiding field poles and said ring-shaped pole shoes are formed by common integral members, each member having slots to separate the accelerating pole piece from the guiding field poles thereof.

30 5. The structure defined in claim 1, wherein said accelerating pole pieces form inner pole surfaces separated by an axial gap along which extends said path for the magnetic flux of the acceleration field.

35 6. The structure defined in claim 1, wherein the mass of the magnetically effective pole shoes defining said outer guiding field zone is small as compared with the mass of the field poles defining said inner guiding field zone.

KONRAD GUND.
